UNITED STATES PATENT OFFICE.

GEORGE H. HUENERGARDT, OF COLLEGEVIEW, NEBRASKA.

WASHING-MACHINE.

No. 832,062.

Specification of Letters Patent.

Patented Oct. 2, 1906.

Application filed January 27, 1905, Serial No. 242,948.

To all whom it may concern:

Be it known that I, GEORGE H. HUENERGARDT, a subject of the Czar of Russia, residing at Collegeview, in the county of Lancaster and State of Nebraska, have invented a new and useful Washing-Machine, of which the following is a specification.

This invention relates to washing-machines.

The objects of the invention are to increase the agitation, and thus the scrubbing action on the clothes; to cause a more effective compression of the air, which will operate to drive the water and suds through the clothes and secure more effective cleansing; to facilitate the operation of the machine; to simplify the manner of combining the suds-box with the supporting-frame, whereby the former may readily be detached when desired; to provide a novel form of operating-handle which will perform the double function of a handle and of a means for limiting the reverse movement of the suds-box when inverted for the purpose of permitting drying thereof, and generally to improve machines of this character.

With the above and other objects in view, as will appear as the nature of the invention is better understood, the same consists in the novel construction and combination of parts of a washing-machine, as will be hereinafter fully described and claimed.

In the accompanying drawings, forming a part of this specification, and in which like characters of reference indicate corresponding parts, Figure 1 is a view in side elevation exhibiting the operative position of the suds-box in full lines and its inverted position by dotted lines. Fig. 2 is a view in vertical longitudinal section. Fig. 3 is a view in vertical transverse section, taken on the line 3-3, Fig. 2, and looking in the direction of the arrow thereon.

Referring to the drawings, 1 designates the suds-box, which is approximately semicylindrical in cross-section, is constructed, preferably, of metal, such as galvanized iron, and is provided with a flat top 2, having a clothes-opening closed by a suitable cover 3, which is held within the opening by frictional contact with the walls thereof and operates in the usual manner to prevent any splashing out of the water when the suds-box is operated.

The suds-box is supported for swinging movement by shafts 4, provided with bases 5, which are secured to the suds-box in any

suitable manner and have their faces adjacent the shaft formed into conical surfaces 6 to work against the inner sides of the shaft-bearings 7, which, as shown in Fig. 1, are ordinary pillar-blocks provided with hinged cap-plates 8, which when thrown back will permit the ready removal of the suds-box from the supporting-frame. By the provision of the conical surfaces 6 friction between the shafts and the bearings will be reduced to a minimum, and any danger of interference between the suds-box and its supporting-frame will be obviated. The supporting-frame comprises pairs of angularly-disposed legs 9, to the upper ends of which are secured the bearings 7, the lower portion of each pair of the legs being braced and connected by crossed tie-rods 10, as clearly shown in Fig. 3.

Each end of the suds-box has secured to it a handle 11, by which the box may be lifted from the supporting-frame, and the supporting-frame has secured to it at each side hinged handles 12, by which the structure as a whole may be transported when necessary.

Secured within the suds-box is a series of dashers 13, which are constructed, preferably, of metal and have their lower ends provided with transverse strips 14, that operate slightly to retard the escape of water in the operation of the suds-box, and thus cause a more violent agitation of the suds than could be secured if these check-strips were omitted. These elements also perform the further function of rubbers to assist in cleansing the clothes.

As will be seen by reference to Fig. 2, the dashers are arranged on opposite sides of the suds-box and on reverse and relatively acute inclines, and by this arrangement when the suds-box is vibrated there will be a rolling or gyratory movement imparted to the suds, which will cause the clothes to be turned upon themselves and be thrown against the dashers, in which act the air will be forced into the pockets 15 between the pairs of dashers and in escaping will force the suds through the clothes, and thereby effect rapid and thorough cleansing.

The operating-handle, to which reference has been made, consists of a lever 16, a hand-grip 17, disposed at right angles thereto, a shank 18, disposed at right angles to the lever and in parallelism with the hand-grip, and an approximately L-shaped attaching member 19, projecting from the shank and secured to the side batten 20 of the suds-box

and to the wringer-board 21 by bolts or screws 21^a. As will be seen by reference to Fig. 1, the lever 16 occupies a plane approximately parallel with the top of the suds-box, 5 and by this arrangement an extended range of movement may be imparted to the suds-box with but slight exertion on the part of the operator. The shank 18 constitutes a stop to engage with one of the legs 9 when the 10 position of the suds-box is reversed, as shown in Fig. 1, and in order to hold the box in this position the top of the suds-box is provided with eyes 22, which are engaged by hooks 23, carried by the legs of the machine, and when 15 in this position, with the cover removed, the suds-box will be permitted thoroughly to drain, and thus dry.

It will be seen from the foregoing description that although the improvements of this 20 invention are comparatively simple in character they are of value and thoroughly effective in securing the purposes designed,

and, further, owing to the manner in which the parts are constructed and assembled that danger of breakage or disarrangement in use 25 is reduced to a minimum.

Having thus described the invention, what is claimed is—

In a washing-machine, the combination with a suds-box provided with a wringer-board, of a handle comprising a lever, a hand-grip arranged at one end thereof, a shank disposed at right angles to the lever and in parallelism with the hand-grip, and an approximately L-shaped attaching member 30 35 projecting from the shank and secured to the suds-box and to the wringer-board.

In testimony that I claim the foregoing as my own I have hereto affixed my signature in the presence of two witnesses.

GEORGE H. HUENERGARDT.
